UNITED STATES PATENT OFFICE.

HEINRICH MITZSCHKE, OF WALDHOF, NEAR KAMENZ, SAXONY, GERMANY.

CONVERTIBLE SKITTLE-ALLEY.

SPECIFICATION forming part of Letters Patent No. 390,247, dated October 2, 1888.

Application filed January 4, 1888. Serial No. 259,788. (No model.) Patented in Germany June 1, 1887, No. 41,641.

To all whom it may concern:

Be it known that I, HEINRICH MITZSCHKE, wood-trader, a subject of the Emperor of Germany, residing at Waldhof, near Kamenz, in the 5 Kingdom of Saxony, Germany, have invented certain new and useful Improvements in Convertible Skittle-Alleys, (for which I have received Letters Patent in Germany, No. 41,641, dated June 1, 1887;) and I do hereby declare 10 the following to be a full, clear, and exact description of the invention, such as will enable others skilled in the art to which it appertains to make and use the same.

The object of this invention is to adapt a 15 part of a skittle-alley to be readily converted into a table, and also readily restored to its former condition as part of a skittle-alley ready for use.

Figure 1 represents a side elevation of a 20 skittle-alley embodying my invention, the skittle-platform being shown in section. Fig. 2 represents a vertical cross-section on the line $x-x$ of Fig. 1. Fig. 3 represents a plan view of the same broken away to show the table- 25 supports. Fig. 4 represents a central longitudinal section of the same, with one section of the floor of the alley raised to form a table; and Fig. 5 represents a vertical transverse section on the line $y-y$ of Fig. 4.

30 A designates two longitudinal bars, of angular iron, forming a bed for the skittle-alley. These bars are in sections, connected by joint-plates e . On said bed, at one end thereof, rests a frame, B, also of angular iron, which serves 35 as a support for the skittle-platform C. On this platform are the pins or skittles c . The wooden floor a of the skittle-alley is supported on cross-bars b , of angle-iron, which rest on the longitudinal bars A of the bed. Side walls, 40 a' , are hinged to the said floor and supported in vertical position by removable braces. One of the sections of the said floor a is provided with supporting-frames g , which are pivoted at the

bottom on supporting bolts or studs f , attached to bars A. The upper ends of these frames are 45 adapted to be bolted to the cross-bars b . Rods h , extending from one frame g to the other, serve as braces therefor.

When the skittle-alley is ready for use as such, the supporting frames are folded below 50 it in the position shown in Fig. 3. When the section having these supporting-frames is to be used as a table, these supporting-frames are turned upward on the studs or bolts f and bolted to the cross-bars b , the section of floor- 55 ing being raised for that purpose. The brace-rods h are then bolted to said supporting-frames, the side walls turned down, and the table is complete.

The construction and combination of parts 50 above described allow the conversion of the table into a part of a skittle-alley, or vice versa, to be effected very speedily and with little trouble. The cheapness of manufacture and the convenience of transportation are also 65 obvious.

Having thus described my invention, what I claim as new, and desire to secure by Letters Patent, is—

The longitudinal bars A, in combination 70 with a skittle-supporting frame, B, and platform C, resting on said bars at one end of the latter, a skittle-floor provided with cross bars b , resting on said bars A, side walls for said floor adapted to turn down, and supports for 75 one section of said floor which are pivoted to bars A and adapted to be attached to cross-bars b for use with said section as a table, substantially as set forth.

In testimony whereof I affix my signature in 80 presence of two witnesses.

HEINRICH MITZSCHKE.
